UNITED STATES PATENT OFFICE.

STANLEY L. GEDNEY, OF MAPLEWOOD, NEW JERSEY.

CLASP.

1,402,594.

Specification of Letters Patent.

Patented Jan. 3, 1922.

Application filed March 8, 1921. Serial No. 450,757.

To all whom it may concern:

Be it known that I, STANLEY L. GEDNEY, a citizen of the United States, and a resident of Maplewood, in the county of Essex and State 5 of New Jersey, have invented a new and Improved Clasp, of which the following is a full, clear, and exact description.

This invention relates to improvements in 10 clasps, and more particularly to clasps for garters and other garment supporters, an object of the invention being to provide a clasp which will operate to securely hold or engage a stocking or other garment and which will permit a quick engagement and release as 15 occasion may require.

My invention is designed particularly as an improvement over the well-known type of slotted or pear-shaped clasp in general use on the market in connection with garment or 20 hose supporters of various types and the invention is designed to overcome defects of such clasps.

Clasps, as heretofore made, perform their 25 functions properly so long as there is a pull or tension on the clasp, but when this pull or tension is released, the clasp will disengage itself from the hose or other garment, and it is the purpose of my invention to so improve the construction of the clasp that it will se- 30 curely hold whether there be tension or not.

With these and other objects in view the invention consists in certain novel features of construction, and combinations and arrangements of parts, as will be more fully herein- 35 after described and pointed out in the claims.

In the accompanying drawings—

Figure 1 is a view in front elevation illustrating my improved clasp.

Figure 2 is a view in rear elevation of the 40 clasp.

Figure 3 is a view in longitudinal section through the center of the clasp.

Figure 4 is an exaggerated view in trans- 45 verse section on the line 4—4 of Figure 1.

Figure 5 is a view in elevation illustrating my improved clasp in operative engagement with a stocking.

1 represents my improved clasp which may be attached to a garter or tab 2 in any 50 approved manner and I have illustrated a slot 3 in the garter for the reception of the tab which is a convenient means of connecting the parts.

The clasp 1 is of the same general pear

shape as the clasps in ordinary use having a 55 slot 5 relatively wide at one end and relatively narrow at its other end, so that the goods of the stocking or hose 6 can be readily projected through the wider end of the slot 5 and then forced into the narrower or reduced end of the slot where it will be effectually gripped and held.

With clasps, as heretofore made, the narrower or reduced end of the slot will operate as a gripping means so long as there is a 65 tension or pull on the clasp, but when this tension or pull is released, the clasp will disengage itself from the hose and to prevent this annoying and defective operation, I provide on the smaller or reduced end of the 70 clasp an integral spring tongue 7. This tongue curves backwardly and inwardly upon the clasp and serves as a gripping means to confine the gripped portion of the hose between the tongue and the body of the 75 clasp, as illustrated in Figure 5.

The tongue 7 is made adjacent its free end with a slot 8 which is preferably tapering or triangular in form, and at the wider end of said slot 8 an inwardly projecting lip 9 is 80 formed preferably by bending the wall of the slot inwardly to form a biting or gripping edge.

When the material of the stocking 6 is positioned through the slot 5 and forced under the tongue 7, a portion of the material will be projected upwardly through the slot 8 in the tongue and the lip 9 will bite into the matter holding it into the narrow portion of slot 5 and prevent possibility of accidental 85 release of the clasp. To further insure the projection of the material through the slot 8 of the tongue 7, I preferably bend the metal of the clasp at the narrower end of its slot so that the walls of said narrower end of the 90 slot are flared outwardly, as shown at 10, and normally project slightly within the plane of the walls of slot 8, as shown clearly in Figure 4. Hence, when the material of the stocking is forced into place under the 100 tongue, as shown clearly in Figure 5, a portion of said material will be projected through the slot 8 of the tongue 9.

It will further be noted that with a device such as above described, the stocking is 105 not only gripped and held by the narrower portion of slot 5, or rather the walls of said slot 5, but is held by reason of the spring

pressure of the tongue 7 and by reason of the fact that a portion of the material projects through the slot 8 in tongue 7 and also by reason of the fact that the lip 9 has a firm biting or gripping contact with the stocking so as to maintain the same in gripping relation with the walls of the slot of the clasp.

With a clasp such as above described, accidental release of the clasp is rendered practically impossible whether there be tension or not upon the clasp, but the clasp can be effectually disengaged by manual manipulation at any time without injury to the material of the stocking or other garment with which it is connected.

While, of course, my clasp is preferably of metal, it is to be understood that it might be of celluloid or any other suitable material which can be adapted for the purpose, and I do not limit myself to the precise details set forth, but consider myself at liberty to make such changes and alterations as fairly fall within the spirit and scope of the appended claims.

I claim:

1. A clasp having a slot therein relatively wide at one portion and relatively narrow at another portion, a clamping tongue on the clasp positioned over the narrower portion

of said slot, and said tongue having a slot 30 therein.

2. A clasp having a slot therein relatively wide at one portion and relatively narrow at another portion, a clamping tongue on the clasp positioned over the narrower portion 35 of said slot, said tongue having a slot therein, and an inwardly projecting lip on said tongue located at one end of the slot in the tongue.

3. A clasp having a slot therein relatively wide at one portion and relatively narrow 40 at another portion, a clamping tongue on the clasp positioned over the narrower portion of said slot, said tongue having a slot therein, said slot in the tongue of general tapering 45 form and positioned over the relatively narrow portion of the first-mentioned slot, and an inwardly projecting lip on said tongue located at one end of the slot in the tongue.

4. A clasp of the character described having a slot therein relatively narrow at one 50 end, a tongue on the end of the clasp projecting over the reduced portion of the slot, a triangular-shaped slot in the tongue, and an inwardly projecting lip at the wider end 55 of the triangularly slotted portion of the tongue.

STANLEY L. GEDNEY.
